UNITED STATES PATENT OFFICE.

ULYSSES G. LEE, OF CHICAGO, ILLINOIS, ASSIGNOR TO ADDRESSOGRAPH COMPANY, OF CHICAGO, ILLINOIS, A CORPORATION OF ILLINOIS.

TWO-PLATEN HAND ADDRESSING-MACHINE.

1,274,905.

Specification of Letters Patent.

Patented Aug. 6, 1918.

Application filed September 10, 1915. Serial No. 49,889.

To all whom it may concern:

Be it known that I, ULYSSES G. LEE, a citizen of the United States, residing at Chicago, in the county of Cook and State of Illinois, have invented certain new and useful Improvements in Two-Platen Hand Addressing-Machines, of which the following is a specification.

This invention relates in general to that 10 class of printing machines now generally known as addressing machines, but which are frequently employed to print a great variety of information as well as addresses. More specifically the invention relates to a 15 printing machine provided with a plurality of separate simultaneously operable platens.

In commercial work, to which this particular class of printing machine is adapted, it is frequently desirable to produce a 20 plurality of separate impressions from the same printing member at different points as, for example, where a record of the impressions made on envelopes, checks, etc., is to be preserved. The record sheet generally 25 comprises a continuous strip of impression receiving material and it is not only inconvenient to insert this strip beneath a single platen after the impression but the possibility of failure to secure a record impression through carelessness of the operator or 30 otherwise makes a record secured in this manner of doubtful value.

It is the object, therefore, of my invention to provide a printing machine having 35 a plurality of platens adapted to coöperate with each printing member at different points in its path of travel through the machine, whereby a plurality of impressions may be made therefrom.

40 A further object of my invention is the provision of means for moving impression-receiving material through the machine, as well as novel means for causing the ribbon through which the impressions are taken to 45 move step by step to continuously present a fresh surface at the impression point.

Further objects and advantages of my invention will be apparent as it is better understood by reference to the following detailed description when read in connection 50 with the accompanying drawing, disclosing the preferred embodiment thereof, in which—

Figure 1 is a plan view of a printing machine according to my invention;

Fig. 2 is a side elevation thereof; Fig. 3 is a vertical section on the line 3—3 of Fig. 2; Fig. 4 is an end elevation of the machine; Fig. 5 is a vertical section on the line 5—5 of Fig. 1, and

Fig. 6 is a detail view of ratchet mechanism for operating the feed rolls for the impression-receiving material.

Referring to the drawings, 1 indicates a 65 suitable base, preferably of cast metal and hollow to lighten the structure and to house a portion of the operating mechanism. Mounted in suitable bearings supported on the base 1 is a rock shaft 2, having an operating handle 3 secured thereto. Clutch collars 4 are secured to the shaft 2 at spaced intervals and provided with teeth 5 adapted to be engaged by corresponding teeth 6 formed on the hubs 7 of the platen arms 8. 70 A set screw 9 is disposed through the hub 7 and adapted to engage the shaft 2 to secure the hub 7 from movement longitudinally thereof. As will be readily understood the platen arms 8 are thus secured to the rock 75 shaft 2 and are adjustable thereon, so that either of the platens 10, secured to the platen arms 8, may be so disposed as to be in inoperative position when desired. Springs 3' secured to the pins 4' and 5' mounted on 80 the platen arms 8 and the base, respectively, normally maintain the platen arms 8 in their upper position.

Secured to the rock shaft 2 is an arm 11 having a roller 12 pivotally mounted thereon 90 which is adapted to engage a track 13 secured to a rock shaft 14 extending longitudinally of the machine, whereby the shaft 14 will be rocked when the shaft 2 is actuated by the hand lever 3, the extreme positions of the track 13 being clearly indicated in Fig. 4. The rock shaft 14 is provided at one extremity with a bevel gear 15 which meshes with a pair of bevel pinions 16, loosely mounted on a transverse shaft 17. 95 The bevel pinions 16 are provided with ratchet teeth 18 which are adapted to be engaged by the pawls 19 pivotally mounted on pins 20 carried by the collars 21 which are in turn secured to the shaft 17. Springs 22, 100 secured to the pawls 19 and to pins 23 mounted in the collars 21, normally force the pawls 19 into engagement with the ratchets 18. As the rock shaft 14 oscillates the bevel pinions 16 and ratchet teeth 18, being on 110

opposite sides of the shaft 14, rotate in opposite directions with respect to each other. The pawls 19 alternately engage and idle over the ratched teeth on the respective bevel 5 pinions, each pawl engaging its pinion when the latter is rotating in the desired direction of rotation of the shaft 17, which is thus caused to rotate step by step.

The transverse shaft 17 is provided at 10 one end with a sprocket 24 which drives a chain conveyer 25, having upstanding lugs 26 secured thereto at intervals, in the direction indicated by the arrow in Fig. 2. A sprocket 27 is mounted on a stub shaft 28 15 at the opposite end of the machine. The chain conveyer 25 is disposed about said sprocket 27.

A magazine 29 is secured to the base 1 at one end thereof and as will be readily understood the lugs 26 passing beneath the magazine 29 will withdraw the printing plates, of any suitable form, therefrom and move them along the bed in position to allow impressions to be taken therefrom when the 25 platens 10 are actuated. The conveyer-actuating means is so arranged that movement is imparted to the chain conveyer 25 through the medium of the ratchets 18 and pawls 19 at each movement of the platens, the chain 30 conveyer 25 moving a distance substantially equal to one-half the length of the printing member when the platens move upwardly and a substantially equal distance when the platens move downwardly. This arrangement 35 prevents too great a momentum in the printing members and consequent overthrow thereof which would result in failure of the printing members to register properly with the platens 10.

40 The impressions are preferably taken through a ribbon 30 which is mounted on spools 31, suitably secured to the shafts 32, rotatably mounted in brackets 33, beneath the base 1. The ribbon 30 is disposed through 45 the guides 34 which change the direction of movement of the ribbon. The shafts 32 are provided with knurled buttons 35 at their extremities, whereby the spools 31 may be manually rotated to move the ribbon 30 50 along the bed of the machine. At their adjacent ends the shafts 32 are provided with ratchets 36 secured thereto and each adapted to be engaged by a pawl 37 pivotally secured to a crank arm 38 fastened to the rock shaft 55 14. A shaft 39, having an operating handle 40, is disposed longitudinally of the machine and provided at its extremity with a pair of disks 41 having pins 42 secured thereto and adapted to engage beneath the respective 60 pawls 37. The pins 42 are angularly disposed with respect to each other and, as is clearly shown in Fig. 5, one of the pawls 37 will be held from engagement with the corresponding ratchet 36 when the other pawl 65 37 engages its corresponding ratchet. Hence

by manipulating the shaft 39 one or the other of the shafts 32 may be actuated from the rock shaft 14 and the ribbon 30 will be automatically moved to continuously present a fresh surface beneath the platens 10 as the 70 machine is operated.

Secured to the rock shaft 14 is a collar 43 provided with a plurality of ratchet teeth 44. A gear wheel 45 is loosely mounted on the shaft 14 and is provided with pawls 46 adapted to coöperate with the ratchet teeth on the collar 43. A pinion 47 is mounted on a stub shaft 48, which carries a friction roll 49 adapted to coöperate with a roll 50 mounted on an arm 51. This arm 51 is pivotally mounted on arm 52 loosely mounted on shaft 52' and is normally pressed into coöperative relation with the roll 49 by spring 53.

An upstanding arm 53' formed integrally 85 with the arm 52 is connected by a pin 54 to a link 57, the opposite end of which is secured to an eccentric pin 58 on a stub shaft 59 suitably supported on the base 1. The stub shaft 59 is provided with an operating 90 handle 60. When the stub shaft 59 is rotated by means of the operating handle 60 in a clockwise direction, viewing Figs. 4 and 5, the arm 52 is rocked through the eccentric pin 58, the link 57, the pin 54 and the arm 95 53' to lift the roll 50 from engagement with the roll 49 or in other words to inoperative position. When the stub shaft 59 is rotated in the opposite direction the roll 50 is again moved to operative position. The impression-receiving material is disposed between the rolls 49 and 50 and since the roll 49 is positively moved in one direction as the platens 10 move toward and from printing position it will be readily understood that the impression-receiving material may be moved between each impression a distance sufficient to allow an impression from the next succeeding plate to be taken thereon.

In the drawing I have illustrated rolls 49 110 and 50 adjacent each of the platens 10 but it is to be understood that the forwarding mechanism for the impression-receiving material may be omitted in connection with either of the platens and that where more 115 than two platens are provided corresponding mechanism for forwarding the impression receiving material may be employed in connection therewith.

The operation of my improved printing 120 machine should be readily understood without further description of the structure thereof. As the operating handle 3 is moved the platens 10 are carried toward and from printing position to coöperate 125 with the printing members which print through the ribbon upon the impression-receiving material in the usual and well-known manner. The printing members are moved step by step from the magazine 29 130

longitudinally of the machine beneath the platens 10, as previously explained, the ribbon 30 moving a short distance at each actuation of the platens 10 to present a fresh 5 surface to the printing members. Envelops, checks, etc., may be fed by hand to receive impressions from one of the platens 10 while a continuous strip of impression-receiving material may be moved by the 10 rolls 49 and 50 transversely of the machine beneath the other platens. Each plate which passes from the magazine will come to rest beneath both of the platens 10 in succession and hence an impression may be 15 made from the printing member on both the envelop or check and the strip of impression-receiving material which serves as a record of the impressions made. If the record is unnecessary either of the platens 20 10 may be moved and secured in inoperative position and the machine may then be employed as a single platen machine. It will be readily understood that I have perfected a printing machine which is adaptable to numerous uses for which a single platen machine may not be used and that the numerous features of novelty coöperate to produce results heretofore impossible in machines of this character. 25

30 It will be obvious that various changes may be made in the form, construction and arrangement of the parts without departing from the spirit and scope of the invention or sacrificing any of its material advantages, the form hereinbefore described being merely a preferred embodiment thereof.

I claim:

1. In a machine of the character described, the combination of a bed, a pivotally mounted shaft, a plurality of independent arms secured to said shaft and adjustable thereon to operative and inoperative positions, a platen mounted on each arm, actuating means for said shaft and means 40 for moving printing members along said bed and adapted to position said members successively beneath said platens.

2. In a machine of the character described, the combination of a bed, a plurality of independent arms secured to said shaft and adjustable thereon to operative and inoperative positions, a platen mounted on each arm, actuating means for said shaft, means for moving printing members along 45 said bed and adapted to position said members successively beneath said platens, and means for automatically moving impression receiving material transversely of said bed beneath said platens.

3. In a machine of the character described, the combination of a bed, a pivotally mounted shaft, actuating means therefore, a plurality of arms, a platen mounted on each arm, an adjustable clutch connection between said arms and shaft and means

for moving printing members along said bed and adapted to position said members successively beneath said platens.

4. In a machine of the character described, the combination of a bed, a pivotally mounted shaft, actuating means therefore, a plurality of arms, a platen mounted on each arm, an adjustable clutch connection between said arms and shaft, means for moving printing members along said bed and adapted to position said members successively beneath said platens, and means for automatically moving impression receiving material transversely of said bed beneath said platens. 75

5. In a machine of the character described, the combination of a bed, a plurality of pivotally mounted arms independently adjustable to operative and inoperative positions, a platen mounted on each of said arms, means for manually and simultaneously swinging said arms to cause said platens to strike impression blows and means for moving printing members along said bed and adapted to position said members successively beneath said platens. 80

6. In a machine of the character described, the combination of a bed, a pivotally mounted shaft, a plurality of arms independently adjustable on said shaft to operative and inoperative positions, a platen mounted on each of said arms, means for swinging said arms and means for moving printing members along said bed and adapted to position said members successively beneath said platens. 95

7. In a machine of the character described, the combination of a bed, a pivotally mounted shaft, a plurality of arms mounted on said shaft and independently adjustable to operative and inoperative positions, a platen secured to each of said arms, manually operable means for swinging said arms, a magazine, means for moving printing members from said magazine along said bed and adapted to position said members successively beneath said platens and means for automatically moving the impression receiving material beneath said platens. 100

8. In a machine of the character described, the combination of a bed, a magazine at one end thereof, means for moving printing members in spaced relation along said bed, a shaft, a plurality of arms independently adjustable on said shaft to operative and inoperative positions, a platen mounted on each of said arms, manually operable means for rocking said shaft to simultaneously move said platens toward and from printing position and connecting means between said shaft and said first mentioned means whereby said printing members are moved successively beneath said platens. 110

9. In a machine of the character described, the combination of a bed, a magazine at one

- end thereof, means for moving printing members in spaced relation along said bed, a shaft, a plurality of arms mounted thereon, an independent platen mounted on each 5 of said arms, means for rocking said shaft to simultaneously move the platens toward and from said bed, and connecting means between said shaft and said first-mentioned means, whereby said printing members are 10 moved forward partway toward printing position as said platens move to printing position and partway toward printing position as said platens return to normal position.
- 15 10. In a machine of the character described, the combination of a bed, a magazine at one end thereof, means for moving printing members in spaced relation along said bed, a shaft, a plurality of arms mounted 20 thereon, an independent platen mounted on each of said arms, manually operable means for rocking said shaft to move the platens toward and from said bed, and pawl and ratchet connecting means between said 25 shaft and said first-mentioned means, whereby said printing members are moved forward toward printing position a distance substantially equal to one-half of their length as said platens move to printing position and an equal distance toward printing 30 position as said platens return to normal position.
11. In a machine of the character described, the combination of a bed, a magazine at one end thereof, means for moving printing members in spaced relation along 35 said bed, a shaft, a plurality of arms mounted thereon, an independent platen mounted on each of said arms, means for rocking said shaft to simultaneously move the platens toward and from said bed, a bevel gear operatively connected to said shaft, a transverse shaft, bevel gears loosely mounted thereon, collars fixed thereto, pawl and ratchet connections 40 between said bevel gears and collars, and a driving connection between said transverse shaft and said first-mentioned means, whereby said printing members are moved forward toward printing position a 45 distance substantially equal to one-half their length as said platens move to printing position and an equal distance toward printing position as said platens return to normal position.
- 50 12. In a machine of the character described, the combination of a bed, means for moving printing devices along said bed, a shaft, a plurality of arms secured thereto, an independent platen mounted on each of 55 said arms, means for rocking said shaft, a second shaft, connections between said shafts, whereby said second shaft is rocked with said first-mentioned shaft, and connections between said second shaft and said 60 first-mentioned means, whereby said printing 65 devices are caused to be successively positioned beneath said platens.
13. In a machine of the character described, the combination of a bed, means for moving printing devices along said bed, a shaft, a plurality of arms secured thereto, an independent platen mounted on each of said arms, means for rocking said shaft, a second shaft, an arm on said first shaft bearing a roller, a slotted arm connected to said second shaft and adapted to be engaged by said roller, whereby said second shaft is rocked with said first-mentioned shaft, and connections between said second shaft and said first-mentioned means, whereby said printing members are caused to be successively positioned beneath said platens. 75
14. In a machine of the character described, the combination of a bed, means for moving printing devices along said bed, a shaft, means for rocking said shaft, a plurality of arms secured to said shaft, an independent platen mounted on each of said arms, a second shaft, connections between said shafts, whereby said second shaft is rocked with said first-mentioned shaft, a ribbon disposed over said bed, and means actuated by said second shaft to cause said ribbon to move along said bed. 80
15. In a machine of the character described, the combination of a bed, means for moving printing devices along said bed, a shaft, means for rocking said shaft, a plurality of arms secured to said shaft, an independent platen mounted on each of said arms, a second shaft, connections between said shafts, whereby said second shaft is rocked with said first-mentioned shaft, a ribbon disposed over said bed, and means to cause said ribbon to move along said bed comprising a pair of shafts, spools thereon, ratchets connected thereto, and pawls operatively connected to said second shaft and adapted to engage said ratchets. 85
16. In a machine of the character described, the combination of a bed, means for moving printing devices along said bed, a shaft, means for rocking said shaft, a plurality of arms secured to said shaft, an independent platen mounted on each of said arms, a second shaft, connections between said shafts, whereby said second shaft is rocked with said first-mentioned shaft, a ribbon disposed over said bed, means to cause said ribbon to move along said bed comprising a pair of shafts, spools thereon, ratchets connected thereto, pawls operatively connected to said second shaft and adapted to engage said ratchets, and means for moving one of said pawls to inoperative position. 90
17. In a machine of the character described, the combination of a bed, means for moving printing members along said bed, a shaft, a plurality of arms secured to said shaft, an independent platen mounted 130

- on each of said arms, manually operable means for rocking said shaft, a second shaft, connections between said shafts, whereby said second shaft is rocked with said first-
 5 mentioned shaft, a ribbon disposed over said bed, means for moving said ribbon along said bed, and operative connections between said second shaft and said printing member moving means and between said second
 10 shaft and said ribbon moving means.
18. In a machine of the character described, the combination of a bed, means for moving printing members along said bed, a shaft, a plurality of arms secured to
 15 said shaft, an independent platen mounted on each of said arms, means for rocking said shaft, a second shaft, connections between said shafts, whereby said second shaft is rocked with said first-mentioned shaft,
 20 means for moving impression-receiving material transversely of said bed beneath the platens, and operative connections between said second shaft and said last-mentioned means.
- 25 19. In a machine of the character described, the combination of a bed, a platen arm supporting shaft, a platen arm on said supporting shaft carrying a platen adapted to coöperate with said bed, a second shaft,
 30 means connected to said second shaft to advance printing devices along said bed, connections between said shafts whereby said second shaft is rocked with said first-mentioned shaft, and means for moving impres-
 35 sion receiving material transversely of said bed beyond said platen comprising a positively driven roll, a driving connection between said second shaft and roll and a resiliently mounted roll disposed in coöpera-
 40 tive relation with said driven roll.
20. In a machine of the character described, the combination of a bed, a platen arm supporting shaft, a platen arm on said supporting shaft carrying a platen adapted to coöperate with said bed, a second shaft, means
 45 connected to said second shaft to advance printing devices along said bed, connections between said shafts whereby said second shaft is rocked with said first mentioned shaft, and means for moving impression receiving material transversely of said bed beneath
 50 said platen, comprising a positively driven roll, driving connections between said second shaft and roll, a resiliently mounted roll disposed in coöperative relation with said driven roll, and means for moving said
 55 resiliently mounted roll into and out of operative position.
21. In a machine of the character described, the combination of a bed, means for moving printing members along said bed, a shaft, a plurality of arms secured to said shaft, an independent platen mounted on each of said arms, means for rocking said shaft, a second shaft, connections between said shafts, whereby said second shaft is rocked with said first-mentioned shaft, a ribbon, means for moving said ribbon along said bed, means for moving impression-receiving material transversely of said bed,
 60 and operative connections between said second shaft and said ribbon moving means and between said second shaft and said impression-receiving material moving means.
